ABSTRACT OF THE DISCLOSURE

A plastic damper spring which can be clipped into place after the assembly of the gongs on a two gong ringer can be positioned to dampen one, both or neither of the gongs thus controlling the volume of the ringer or dampening unwanted party-line caused noises.

This invention relates to telephone ringers and more particularly to the volume controls used with such ringers.

Most of the presently available volume controls used in conjunction with telephone ringers have a deleterious effect on the frequency response of the ringer. For example, one prevalent ringer volume control uses a cam mounted gong. When the gong is rotated on the cam it is positioned closer to or further from the hammer. When the gong is closer to the hammer, the hammer motion is damped by the gong but the hammer does hit the gong with greater force thus resulting in a louder ring but a modulated frequency response. When the gong is further from the hammer there is less damping but the gong is also struck with less force.

Another frequently used method for controlling the volume of the ring is to dampen the hammer swing directly. This is accomplished by various cam dampeners directly abutting the hammer arm to restrict its swing.

Gong dampers have been used for dual ringer gongs for selectively dampening gongs in the tune ringers of frequency selective party line systems. The gong dampers are advantageous in that they do not adversely effect the frequency response of the ringer.

The gong dampers used heretofore have been relatively complicated assemblies requiring a plurality of parts and only useful either for desk sets or wall phones. In addition, the dampers have required relatively extensive dismantling of the ringer for mounting. For example, such dampers have been disclosed in U.S. Patent No. 2,808,019 assigned to the assignee of this application.

Accordingly, it is an object of this invention to provide a new type of gong damper for use in controlling ringer volume.

A related object is to provide a new ringer having improved frequency response characteristics using the gong damper to effectively prevent the ringer from operating responsive to a related frequency signal in frequency selective party line systems.

A further object of the invention is to provide a unitary plastic selective gong damper which can be clipped into its operative position after the ringer is otherwise fully assembled.

Yet another object of the invention is to provide a unitary gong dampening member that can be used to control the volume of ringers used either on desk subscriber telephones or on wall hung telephones.

In accordance with a preferred embodiment of the invention the selective gong damper comprises a molded unitary plastic member, designed to be removably spring clipped to a slot in the frame. Centrally located on the damper is a spring clip arrangement. On each side of the spring clip of the damper is a resilient damping arm which in the mounted position cooperates with camming surfaces of the ringer frame to selectively dampen the first gong,

2

the second gong or both gongs. Means for positioning the dampening means, such as a knob means, is integrally provided on the plastic member to extend through a slot in the desk set and thereby enable the manual damping selection. Similarly, an arm with a fork opened toward the gong is integrally provided for capture by the volume adjustment bar used on wall type telephones. This enables the gong damper position to be varied using the same unity member that is employed with desk sets.

10 The above mentioned and other features of this invention and the manner of obtaining them will become more apparent, and the invention itself will be best understood by reference to the following description of an embodiment of the invention taken in conjunction with the accompanying drawings, in which:

FIG. 1 is a top view of a dual gong ringer shown mounted on the bottom plate of a desk set;

FIG. 1a is a pictorial sectional view taken along line 1—1 of FIG. 1;

20 FIG. 2 is a perspective view of the unitary plastic member comprising the gong damper;

FIG. 3 is a view of the bottom of the ringer showing the damper mounted in its operative position;

25 FIG. 4 is a view looking down on the gongs of the ringer with the damper mounted in its operative position;

FIG. 5 in schematic views a, b and c show the three selective positions of the gong damper;

30 FIGS. 6 and 7 show how the gong damper is positioned to control the ringer volume on a desk set and on a wall set respectively.

In FIG. 1 the ringer which may be of the type described in detail in U.S. Patent No. 3,172,100 and assigned to the assignee of this invention is shown mounted to the base plate 12 of a desk set. Only a portion of the base plate is shown. The ringer is mounted to the base plate by means such as screws 13.

The ringer comprises a frame 14 including a shelf-like integral section 15. Rounded disk like sections 16, 17 are provided for mounting the gong assemblies.

40 Each of the disk-like sections 16, 17 has mounted thereon in a well known manner a gong such as gongs 18, 19 respectively. The gongs are shown cut away to disclose a damper mounted to the frame shelf-like section 15 behind the gongs.

45 The electromechanical actuating portion of the ringer comprises an electromagnet made up of coil 21 and an L-shaped core 22. The core 22 is clamped to the frame 14 by means, such as tabs 23 of plate 24 held to the frame 14 by screws 26.

50 The magnetic circuit is completed by a shunt bar 27 that extends from an end of one leg of the L-shape core 22 to the end of the other leg of the L-shaped core 22. The shunt bar 27 is fastened to the frame 12 by screws 28, 29.

55 A permanent magnet 31 abuts the shunt bar at section 32. The magnet acts to magnetically bias the electromagnetic circuit.

A drive rod 34 is fixedly attached to an inverted L-shaped armature 33 by any well known means. The armature 33 is attached to the frame 14 by reed spring means. The clapper assembly and the cooperating L-shaped armature 33 and drive rod 34 are attached to bracket 36 which is fixedly attached to frame 14 by screws such as screw 37.

65 FIG. 1a best shows the unique manner of mounting the permanent magnet which makes possible an improved frequency response characteristic.

As shown in FIG. 1a the magnet abuts the shunt bar 32. Other than the magnetic attraction therebetween there is no fastener between the shunt bar 32 and the magnet 31.

Means are provided for positioning and holding magnet 31. In greater detail, the magnet 31 is properly positioned with respect to armature 33 by block 38 which is fastened to the frame 14 with screw 39. The magnet is retained in place by pin 41 which depends from bracket 34 to abut magnet 31.

As is also best shown in FIG. 1a the reed spring 42 which supports the armature 33 is clamped between the bracket 36 and the frame at section 14a. The armature 33 depending from the reed spring 42 vibrates responsive to the actuation of coil 21 with alternating current of a specific frequency.

Responsive to the energization of the coil, the armature 33 vibrates about the reed spring 42 and thereby actuates the drive rod 34. The drive rod 34 is mechanically tuned to the ringing frequency by varying the position of weight 43 located at or near the top of the drive rod 34. The drive rod 34 in vibrating causes the clapper assembly comprising clapper rod 44 and clapper 46 to oscillate and strike the gongs.

The weight 43 and gongs 18, 19 are broken away in FIG. 1 to better show the inventive gong damper 47 mounted behind the gongs.

The damper 47 is fabricated of soft, flexible "lossy" material such as Lexan. By the term "lossy" is meant a substance or material having as a characteristic property a high loss of energy due to its internal working or bending responsive to mechanical vibrations, such as: rubber, lead, certain soft plastics, elastomers and the like, for example.

FIG. 2 shows the unique shape of gong damper 47. As shown therein the damper 47 comprises a main horizontal bar 48. There are projecting portions at each end of bar 48. For example, side 49 of bar 48 is equipped with projecting portion 51 which extends slightly below and forward of the main bar body but in the same plane as the main body.

Side 52 of bar 48 has integrally appended thereto a inverted C-shaped section 53 designed to clamp and ride on the cam sections of the ringer frame. Section 53 protrudes to the front of the plane of the main horizontal bar 48. The protrusion enables section 53 to extend through a slot in the base of the telephone set where it is used for manually manipulating the damper 47 to selectively control the volume of the ringer.

Immediately above the main horizontal bar 48 is the wall set lever entrapping bar 54. One end of the bar 54 comprises a hook-like section 56 which is designed to fit around the volume control lever of wall hung telephones. The bar 54 is broken away from the main bar 48 at the joining neck 57 if the damper 47 is used on a desk set.

Means are provided for clipping the damper 47 into place. More specifically, immediately below the main horizontal bar 48 is the transverse bifurcated clamp section 57. The top of the clamp section 58 extends back from the bar section 48 and is normal thereto. An L section 59 depends from horizontal clamp section 58 to form the opposing side of the clip. The resiliency of the material enables the bifurcated clamp section to clip onto a slot in the frame.

The attachment and operation of the damper 47 is better seen in FIGS. 3 and 4. Therein is shown the gongs 18, 19. Weight 43 and hammer 46 are in their normal rest position. The rear of the porch section 15 is provided with cam section 61, 62 for controlling the proximity to the gongs of the portions of the damper that are contiguous to the gong. The cams 61, 62 are located to vary the proximity of the sections 49, 52 to the gongs 17, 18 respectively, as a function of the horizontal movement of the damper spring 47.

The cam surface 61 is smoothly rounded and protrudes progressively further from the gong in the direction away from the center line of the ringer. The cam surface 62 on the other hand, may be ratcheted with grooves such

as grooves 63, 64. The ratchet grooves enable the damper 47 to be moved in steps.

More particularly, the damper 47 clips onto the ringer when the L-section 59 of clamp section 57 is inserted into slot 66 in shelf 15. FIG. 3 illustrates the damper 47 in a broken view to more clearly show how it is easily attached to a completely assembled ringer. The protrusion section 51 rides on cam 61 when the damper 47 is moved to the left in slot 66. The vertical portion of C-section 53 cooperates with the detents provided by grooves 63, 64 to stop the movement of the damper in a step-wise manner. In addition, the vertical portion of the C-section 53 acts as the cam rider to control the proximity of section 52 of damper 47 to gong 19. The portion of C-section 53 furthest from the ringer may be knurled as shown at 67 to make it easier to manipulate section 53 which in turn facilitates manipulation of the damper therewith.

FIG. 4 shows the damper 47 as used in a wall set. More particularly, horizontal section or arm means 54 is shown terminating in claw section 56. The claw 56 is shown operatively surrounding lever 68 which is a component of a wall type telephone. The section 54 is shown having webbing 69 extending between the front of the claw 56 and the main portion of section 54. The webbing serves as a strengthening rib.

The damper 47 is manipulated in the directions of the arrowheads shown in FIGS. 3 and 4. The position of the damper in detents on ratchet grooves 63, 64 or at the ends of the cam surfaces determines the volume of the ring.

More particularly, FIG. 5 shows how the damper may have three positions. FIG. 5a shows the first position. In the first position as illustrated in FIG. 5a the C-section 53 is to the right of the projection of the grooved cam surface 62. The clip section 57 is at the right hand end of the slot 66 and consequently, the cam riding section 51 is to the right of cam surface 61. As a result both sections 49 and 52 of damper spring 47 abut gongs 18 and 19 respectively. Thus, maximum damping is achieved in the position shown in FIG. 5a.

When the damping spring 47 is moved until the vertical portion of the C-section 53 is in groove 64, then the clip section 57 is approximately at the center of the slot 66. The section 52 of spring 47 is moved away from its abutting position relative to gong 19 because the cam riding surface of C portion 53 cooperates with cam surface 62. This moves the damping spring 47 away from gong 19 and leaves a space therebetween. The section 49, however, still abuts gong 18 to dampen its vibrations because the cam surface 61 has as yet not been reached by cam riding section 51. Thus, in position 2 (FIG. 5b) only one gong (19) is damped.

In position three shown in FIG. 5c the clip section 57 is at the left hand side of the slot 66. The cam riding section 51 abuts cam surface 51 which causes section 49 to move away from abutting gong 18. The vertical portion of C-section 53 rests in groove 63 on cam surface 62. Thus, section 52 is also separated from gong 17. Therefore, neither of the gongs are damped and the ringer volume is maximized in the third position.

FIG. 6 shows the bottom of base 12 of a desk set with C-section 53 protruding through slot 71 therein. The legs of the stand such as leg 72, assures that the base is sufficiently removed from the top of any table upon which the desk set rests to prevent obstruction of section 53. To vary the volume of the ringer the subscriber merely picks up the telephone set and moves protruding section 53 as desired.

FIG. 7 depicts a wall type telephone with the handset removed. The hookswitch 74 is shown. At the bottom of the telephone lever 68 protrudes through a slot, not shown. The volume of the ringer is adjusted when the subscriber moves lever 68 as desired. The movement of lever 68 causes damper 47 to move since claw 56 of sec-

tion 54 surrounds lever 68. Thus, when lever 68 is moved to the left, for example, the damper 47 is also moved to the left.

It should be noted that the damper 47 is designed to be mounted on the ringer after the ringer is completely assembled. This is easily accomplished by clipping the damper to the ringer at slot 66. If the telephone is a desk set, then arm 54 is broken away from horizontal section 48. The damper 47 of FIG. 3, for example, shows the damper without arm 54 while FIG. 4 shows the damper with arm 54.

The ability to mount the damper in a completed assembly means that the dampers and ringers can be separately sold and shipped. That is, an operating company can purchase ringers and dampers separately and the installer can supply a damper if and when the subscriber station requires the damper.

While the principle of the invention have been described above in connection with specific apparatus and applications, it is to be understood that this description is made only by way of example and not as a limitation on the scope of the invention.

I claim:

1. In combination, a ringer comprising a frame having mounted thereon gongs and a gong striking electromagnetic mechanism including clapper means for striking the gongs, said combination comprising unitary gong dampening structure, means for slidably securing said dampening structure to the frame, said dampening structure comprising a horizontal bar made of lossy material, a protruding section integrally appended to said bar extending through a slot in said frame enabling sliding movement of the said dampening structure along said frame, cam riding means at each end of said bar, means at each end of said bar for abutting each of said gongs respectively, said frame including cam surfaces, means for positioning said dampening structure so that said cam riding means selectively abut said cam surfaces to adjust the contiguous abutting relationship of said dampening structure to each of said gongs responsive to the position of said dampening structure, clip means are provided integral to and depend-

ent from said horizontal bar, said clip means centrally located on said bar and shaped to cooperate with said slot in said frame for slidably securing said bar to said ringer frame.

5 2. The dampening structure of claim 1 wherein knob means are provided on said bar for manually sliding said bar to position said bar to abut both one or neither of said gongs.

10 3. The dampening structure of claim 2 wherein said knob means is at one end of said bar and comprises said cam riding means.

15 4. The dampening structure of claim 3 wherein said knob means is C-shaped to connect to said frame, said C-shaped knob depends from the bottom of said bar and protrudes to the front of said bar.

20 5. The dampening structure of claim 4 including arm means commencing at the center of said bar and extending parallel thereto, hook means terminating said arm, and actuating lever means captured by said hook means for slidably operating said bar.

25 6. The dampening structure of claim 5 wherein at least one of said cam surfaces comprises ratchet grooves, and means on said C-shaped knob for cooperating with said grooves whereby said dampening structure is positioned in a stepwise manner.
